UNITED STATES PATENT OFFICE.

FRANK W. GERLACH AND FRANK W. MOORE, OF KENTON, OHIO.

GUIDE FOR SEWING-MACHINES.

SPECIFICATION forming part of Letters Patent No. 705,653, dated July 29, 1902.

Application filed February 6, 1902. Serial No. 92,836. (No model.)

To all whom it may concern:

Be it known that we, FRANK W. GERLACH and FRANK W. MOORE, citizens of the United States, residing at Kenton, in the county of 5 Hardin and State of Ohio, have invented certain new and useful Improvements in Gage Attachments for Sewing-Machines; and we do declare the following to be a full, clear, and exact description of the invention, such 10 as will enable others skilled in the art to which it appertains to make and use the same.

The invention relates to gage attachments for sewing-machines.

The object of the invention is to provide a 15 device of this character which shall be simple of construction, durable in use, comparatively inexpensive of production, efficient in action, and which may be attached to the arms of sewing-machines of the various types now in 20 general use and which when not in use may be swung upwardly out of the way and be held in place in close relation to the under side of the sewing-machine arm.

With this and other objects in view the invention consists of certain novel features of 25 construction, combination, and arrangement of parts, which will be hereinafter more fully described, and particularly pointed out in the appended claims.

30 In the accompanying drawings, Figure 1 is a side elevation of the sewing-machine top and the sewing-machine arm attached thereto, illustrating the application of my invention, showing in full lines the attachment in 35 position for use and in dotted lines the attachment supported in position out of use. Fig. 2 is a top plan view of the attachment. Fig. 3 is a longitudinal sectional view through the attachment when in folded position. Fig. 40 4 is a transverse sectional view on line $x-x$ of Fig. 3. Fig. 5 is a sectional view on line $y-y$ of Fig. 2; and Fig. 6 is a detail side elevation of the upper end of the attachment, showing the locking-plate.

45 Referring to the drawings, 1 denotes a sewing-machine arm, and 2 denotes an attaching-plate having suitable screw-holes 3, by means of which it is secured to the under side of the arm and provided at its outer end with an ex- 50 tension 4, hinged thereto by a horizontal pivot 5. This plate is provided with a catch 6,

which may be formed of a tongue, struck out from the plate and projecting downwardly.

7 and 8 denote the extensible parts of the gage, which are connected together and mounted to slide one upon the other, the connection preferably being made by forming one of the bars—for instance, the bar 8—with guide tongues or lugs 9, which project upwardly and over the bar 7 and permit of one having 6c a sliding engagement with the other. These bars are locked to each other in adjusted position by a set-screw 10, which works through a slot 11, formed in the bar 8, and engages a screw-threaded aperture 12, formed in the 65 bar 7. The lower end of the bar is provided with a gage-foot 13, which is adapted to guide the material to the needle.

The bar 7 of the extensible gage is pivoted to the hinged extension 4 by a pivot-bolt 14, 70 which is arranged in a plane at right angles to that of the pivot 5 and permits of the gage being swung inwardly toward the operator. To prevent the gage from swinging outwardly out of parallelism with the hinged extension 4, 75 we provide the gage with a stop 15, which is in the form of a lip struck out from the bar 7 and which is adapted to abut against the hinged extension 4, and thus prevent the outward-swinging movement of the gage. The 80 gage is made extensible in order to adapt it to the work being operated upon.

In order to prevent the gage being accidentally raised from the bed-plate while in use, we provide a locking-plate 16, which is 85 attached to the inner end of the pivot-pin 5 and is provided on its upper forward edge with an inwardly-projecting lug 17, which engages the upper surface of the extension 4, the plate 16 being also provided at its opposite lower corner with a screw 18, which when screwed through the plate bears on the under side of the extension 4, as shown in Fig. 6 of the drawings. It will thus be seen that when the gage rises or lowers for any purpose the plate must necessarily turn on the pivot-pin 5 and move therewith, and it will be obvious that when the plate is locked in any position the gage is also locked in that position. The means employed for locking 90 the plate, and therefore the gage, consists in providing the rear edge of the plate with a 95

segmental slot 19, through which passes a set-screw 20, which is screwed into a threaded opening in a lug 21, projecting downwardly from the portion 2 of the gage. Thus it will be seen that when the gage-foot 13 has been adjusted on the bed-plate at the required place and the screw 20 tightened against the plate 16 the parts will be locked against any upward movement.

In operation when the parts are in the position shown in Fig. 1 should it be desired to discontinue the use of the gage it is grasped and swung inwardly in a direction toward the operator, turning upon the pivot 4. After it has been swung inwardly in this manner to free its lower end from the bed-plate of the machine it is then swung upwardly on the pivot 5 and then swung outwardly on the pivot 14 to parallel it with the then folded extension 4 and to engage it with the catch 6, which holds it in a folded position. (Shown in dotted lines in Fig. 1.) It will thus be seen that by hinging the gage to the extension by the pivot 14 said gage may be lowered into and raised from engagement with the bed-plate of the machine without the necessity of adjusting the bars 7 and 8, which would require considerable more time than the simple swinging of the catch into another position.

From the foregoing description, taken in connection with the accompanying drawings, the construction, mode of operation, and advantages of the invention will be readily understood without requiring a more extended explanation.

Various changes in the form, proportion, and details of construction may be made within the scope of the invention without departing from the spirit or sacrificing any of the advantages thereof.

Having thus described our invention, what we claim, and desire to secure by Letters Patent, is—

1. The combination with a gage, of a plate adapted to be attached to the arm of a sewing-machine, an extension hinged to said plate by a transverse pivot, a vertical pivot for hinging the upper end of said gage to the outer end of said extension, and means for holding the gage in elevated position under the arm of the sewing-machine, said means consisting of a catch-hook projecting from said plate, substantially as set forth. 45

2. The combination with a gage, of a plate adapted to be attached to the arm of a sewing-machine, an extension hinged to said plate by a transverse pivot, a vertical pivot for hinging the upper end of said gage to the outer end of said extension, means for holding the gage in elevated position under the arm of the sewing-machine, and means for limiting the outward movement of the gage with respect to the extension, said means consisting of a stop-lip projecting downwardly from the gage and adapted to abut against the extension, substantially as set forth. 55

In testimony whereof we have hereunto set our hands in presence of two subscribing witnesses.
